COSMETIC APPLICATOR

Madeline M. Bardugon, Verona, N. J.

Application January 25, 1947, Serial No. 724,285

1 Claim. (Cl. 15—206)

1

This invention relates to novel devices and more especially to those finding application in the field of cosmetics. In one of its specific aspects this invention relates to the combination of a lipstick rod and a spreader therefore carried by a single unitary support and carrying means. A more specific aspect of this invention is directed to a novel device for spreading lipstick cosmetic on the lips generally after the application thereto by the lipstick rod.

The colored cosmetic generally termed lipstick has for many years been used to enhance the color of lips of human beings. This cosmetic ordinarily is of red color or of a shade of red and is of a greasy or "waxy" nature and is purchased on the open market in rod or small roll form. The rod or roll of lipstick is contained in a short tube or casing and may be moved into and out of the tube. When this cosmetic is to be applied to the lips, the rod of lipstick material is partially projected through the open end of the tube containing it and the free end of the lipstick is rubbed across both the upper and lower lips. Such an application of the lipstick on to the lips is not in itself entirely satisfactory because due to the broad free end of the relatively soft easily applied cosmetic the proper or desired shape of this cosmetic over the lips is not possible. Consequently it has been necessary to employ the end of the small finger in an effort to evenly spread the lipstick and to attempt to shape the deposited cosmetic. This procedure has a number of disadvantages among which are (1) the end of the finger becomes coated with the highly colored lipstick material which adheres tenaciously to the skin and is not easily removed therefrom, (2) because the end of the little finger is coated with the lipstick material, danger of transferring this material onto the user's clothing, such as an evening gown is ever present, particularly since the necessary means for removing the lipstick are not always available at those places where the lipstick is applied, (3) by using the end of any finger, it is very difficult, if not impossible to obtain an even distribution of the cosmetic and to properly shape the deposit. This invention was made in order to overcome the above as well as other disadvantages.

An object of this invention is to provide a unitary device including a lipstick rod and lipstick spreader making readily available the necessary elements for applying and shaping such a cosmetic and eliminating the danger of accidental lipstick spotting on the clothing and also elimi-

nating the soiling of hands with lipstick material and consequently making it entirely feasible to apply the lipstick and to shape it in any desired place.

5 Another object of this invention is to provide a novel device for shaping the lipstick on the lips after application of a deposit thereof on the lips.

Still another object of this invention is to provide a lipstick applicator for evenly applying and 10 finely shaping lipstick material on the lips of the user.

Still another object of the invention is to provide a single unitary assembly which includes a source of lipstick material, and a spreader therefor so that the material may be deposited and shaped with the same unit.

These as well as other objects of this invention will in part be obvious and will in part appear hereinafter.

20 Briefly the invention comprises a holder or carrier which may be in the nature of a hollow tube having a lipstick and short tube carrier therefor located in one end of said hollow tube and a lipstick spreader supported in a carrier 25 therefor located in the other end of said hollow tube. The novel lipstick spreader may comprise a holder carrying a fairly rigid yet resilient rod having secured thereto tufts, knots or bunched filaments of cotton, wool, nylon, paper, silk, rayon, etc. which are capable of retaining and of evenly spreading the cosmetic upon application of the spreader thereto. An alternative embodiment of 30 a spreader is a pointed felted element. The lipstick material may be applied directly to the 35 spreader before application of this material to the lips and the so loaded spreader may be used to coat and shape the lips, thus obviating the necessity of first depositing the material on to the lips by the use of the lipstick rod and then 40 spreading and shaping the deposited cosmetic with the spreader.

This invention accordingly comprises the novel articles of manufacture possessing the features, properties and relation of elements which will be 45 exemplified in the articles hereinafter described, and the scope of the invention will be indicated in the claim.

Fig. 1 is a view in side elevation of the combination of a tubular carrier having the novel spreader located in one end thereof and the lipstick at the other end thereof.

Fig. 2 is an enlarged vertical cross sectional view of a form of support and a spreader shown in perspective and coupled with said support.

Fig. 3 is a perspective view of an element which

may be employed in the production of a particular type of spreader.

Fig. 4 is a view in perspective of the spreader element after shaping and before coupling with a holder or support therefor.

Fig. 5 is a view showing the manner of shaping the lipstick on the lips after a deposit of this cosmetic has been made thereon.

Fig. 6 is another embodiment of a spreader which may be substituted for the spreader of Figs. 3 and 4 and substituted for these elements in the construction shown in Fig. 2.

Fig. 7 is a cross sectional view of still another embodiment of the invention.

According to this invention there is provided a hollow container or carrier 10. This container or carrier 10 may be composed of any desirable material, such as metal, wood, plastic or the like and it may be either transparent or opaque depending on the ultimate requisite design. In one of its forms, the container or carrier 10 may be a hollow metal cylinder having a highly polished outer surface and bayonet slot 12 at the ends thereof. An ordinary rod (not shown) of lipstick is carried in an open ended lipstick case 13 having a base 14 whose diameter is greater than that of container 10. The outside diameter of case 13 is slightly less than the interior diameter of container 10. This rod of lipstick cosmetic while not in use is located within the limits of the short tubular case 13 but its free end may be moved out of the free end thereof when it is desired to use it. Projecting outwardly from the case 13 is a pin 15. The lipstick rod and casing 13 may be inserted into one of the open ends of the container 10 and may be demountably coupled therewith by locating the pin 15 in the closed end of the bayonet slot.

A novel lipstick spreader or applicator 16 may be located in the other end of the container 10. The spreader 16 may comprise a knurled knob or base 17 having an upwardly extending elongated tubular retainer 18 integral therewith. The base 17 is recessed to provide an annular shoulder 19 whose inside diameter is slightly less than the internal diameter of the container 10 and whose outside diameter approximates the corresponding dimension of container 10. Carried by the tubular retainer 18 is the spreader proper 20. The spreader 20 may be of any convenient design but is preferably of the type shown in Figure 3. This spreader 20 may comprise short cotton, wool, rayon, nylon, etc. fibers which are relatively soft and pliable and capable of carrying the lipstick material and of spreading it without streaks. These short and soft fibers are located between a pair of thin wires which are disposed in parallel relation to each other and then twisted tightly around each other so that the fibers extend substantially radially in all directions forming a thin but soft and thick outer fiber coat.

The length of spreader 20 may be folded over to provide a loop 23 and legs 24. The spreader 20 of this configuration may have the legs 24 thereof inserted in the tubular retainer 18 which may be compressed to firmly hold the same therein. If desired and in order to assure retention of the loop 23, the legs 24 may first be twisted around each other and then inserted in and coupled with the retainer 18. If desired the loop portion 23 of spreader 20 may be loaded or coated with the lipstick material before its first use if desired, and may be employed both as an applicator and spreader. The base 17 has a pin for coupling the

spreader and its holder to the other open end of tube 10 in a similar manner to the case 13.

Instead of employing the spreader 20, a spreader 21 as shown in Fig. 6 may be employed. 5 This spreader 21 is a felted short rod of felted cotton, paper, cellulose or other soft absorbent fibers similar to the fibers of spreader 20. The upper or spreading end of the rod 21 is conical and its cylindrical section fits into and is secured to the upper end of tube 18. The free end of the spreader 21 may be tapered in some other manner than being conical as shown.

In operation, when the separate lipstick rod and casing 13 are employed, the lipstick material is deposited on the lips well within the outer limits to be attained. Then the lipstick and casing are recoupled with container 10 and the spreader and holder therefor is removed from container 10. With the knurled base 17 held between the thumb and the first two fingers and the spreader 23 or 21 disposed towards the lips to be shaped, spreader 23 or 21 may be readily and easily moved to spread the deposited lipstick material and to obtain with nicety and no smearing the shape desired. When the spreader 20 is used the deposited lipstick material is readily absorbed or carried by the fluffy soft fibers and the twisted wires form a fairly stiff yet somewhat resilient support. When the spreader 21 is used in place of element 20, the soft felted point forms a fairly stiff yet somewhat soft and resilient element.

In another embodiment of this invention there may be provided a lipstick supply chamber 30 having a somewhat conical or tapered upper end 31 having a central small opening therethrough. The body of the chamber 30 is essentially of cylindrical form. This chamber 30 may be in the form of a closed lower end collapsible tube or it may be rigid throughout. If desired the lower end of the chamber 30 may have a bottom closure 35 with a central opening therein accommodating an interiorly threaded sleeve 33. Located in the lower part of said chamber 30 is a piston 34 having a threaded piston rod 32 connected thereto and depending therefrom. The piston rod 32 extends through the opening in the closure 35 and makes threaded engagement with the collar 33. That end of the piston rod 32 located exteriorly of the chamber 30 has a winged nut or knurled knob 36 secured thereto for turning the rod 32 and for moving the cylinder 34 towards or away from the forward or tapered end 31 of the chamber 30. Secured to the cone 31 extending therefrom and communicating with the opening therein is a slender hollow tube 37. Concentric with the tube 37 and also secured to the cone 31 is a hollow tube 38 whose upper limit is substantially that of the upper limit of tube 37. A spreader 20 which is bent in the form of an inverted U has its legs disposed and locked in the space between the tubes 37 and 38. This inverted U may be somewhat enlarged at its looped end to provide a space between the fold or loop and the upper end of the tube 37. 60 The lower end of the cone 31 may have a threaded collar 39 secured thereto and an elongated cover cap 40 of substantially the same diameter as that of the chamber 30 may be threadedly connected to the chamber 30 through the collar 39. In this embodiment of the invention the chamber 30 is filled with a quantity of lipstick material 41 either in the form of a rod or in a somewhat softer or pasty form. When it is desired to use the device, the cap 40 is unscrewed therefrom. Then the knob 36 is turned where-

upon the piston 34 is moved upwardly forcing or extruding some of the material 41 up through the tube 37 into the space between the U shaped portion of the spreader and the upper end of the tube 37 and on to the U shaped portion of the spreader itself. The U shaped portion of the spreader is thus loaded with the desired amount of lipstick material and the device is now ready for application, spreading and shaping of the cosmetic.

While the various aspects of this invention have been described in detail, they are not to be limited thereby because these various embodiments are merely illustrative and are subject to various changes and modifications.

I claim:

A lipstick spreader comprising an assembly of a plurality of short, soft and pliable fibers located between, disposed along substantially the entire length of, and carried by a pair of wires twisted around each other so that the fibers extend approximately radially in all directions forming a soft and thick outer fiber coat along substantially the entire length of said wires, a support for said assembly, said support comprising an enlarged head adapted to be held by a thumb and the first two fingers of a normal hand, and a relatively narrow and elongated member extending from said head and having a longi-

tudinally extending recess therein, said assembly being in the shape of a loop with the legs thereof extending into said elongated opening with substantially only the loop portion thereof located outside of said member, the length of said legs in said opening being substantially greater than the greatest dimension of said loop.

MADELINE M. BARDUGON.
